described and illustrated in my previous and co-pending application for patent, filed in the United States Patent Office on January 15, 1929, Serial No. 300,000, the disclosure of which is incorporated herein by reference, and which application is entitled "Sanitary Napkin Belt." The present application is a continuation-in-part of the above-mentioned application, and the disclosure of which is incorporated herein by reference.

This invention relates to fasteners, and more particularly to an improved means for attaching a sanitary napkin to a belt.

UNITED STATES PATENT OFFICE

ARTHUR W. GAVITT, OF CHICAGO, ILLINOIS, ASSIGNOR TO A. STEIN & COMPANY, OF CHICAGO, ILLINOIS, A CORPORATION OF ILLINOIS

FASTENER

Application filed October 16, 1929. Serial No. 400,120.

This invention relates to fasteners, and more particularly to an improved means for attaching a sanitary napkin to a belt.

The objects of my invention are to provide simple but effective means for securely holding or securing a sanitary napkin to a belt; and in general, it is the object of my invention to provide an improved structure of the class described. Other objects and advantages of my invention will be understood by reference to the following specification and accompanying drawings in which I have disclosed a sanitary belt embodying a preferred form of my invention.

In the drawings:

Fig. 1 is a perspective illustrating a sanitary belt.

Fig. 2 is a front elevation of one of the pendants whereby the ends of a sanitary napkin are secured to the belt.

Fig. 3 is a plan of the reverse side of Fig. 2, and

Fig. 4 is a section on the line 4—4 of Fig. 2.

Referring now to the drawings, there is shown a belt proper 5 which is designed to be positioned about the hips, suitable means, such as sliding buckles 6 and 7, being provided for permitting adjustment of the belt 5 in a well-known manner. For securing the napkins to the belt, pendant clasps 8 and 9 are provided.

The pendant clasps 8 and 9 are of like construction, the only difference being that one is reversed with respect to the other, and hence I will proceed to describe only one of them.

The pendant 9 includes a length or strip 10 of flexible material, preferably a suitable elastic material. This strip 10 is secured or attached to the belt 5 by means of a loop 11 which is stitched to the upper end of the strip 10, the said loop 11 fitting around and being slidable along the belt 5. The strip 10 is provided with a slide buckle 11' through which

the strip is threaded, as best shown in Fig. 4, to form a loop 12 at its lower end.

A pair of clasp members 13 and 14 are carried by the looped portion 12 of the strip 10, each of these clasp members being provided with an opening 15 adjacent but spaced downwardly from its upper end. Each clasp member is also provided with an opening 16 through which the looped portion 12 also passes as shown, and through which one of the tabs 17 of the napkin is passed substantially as shown in Fig. 4 to secure the napkin to the belt. The openings 16 in the clasp members 13 and 14 are spaced downwardly from the openings 15 in the said members so as to provide bar portions 17—17 intermediate the respective openings. The openings 15—15 being spaced downwardly from the upper ends of the respective clasp members, leave upper end bar portions 18—18.

The spacing of the openings 15 and 16 of the clasp members is preferably such that the bar portions 17—17 are fairly wide as clearly indicated, and each of the clasp members is preferably made of a suitable non-metallic material such as celluloid.

As clearly shown in Fig. 4, the strip 10 is threaded through the openings 15 and 16 of each of the clasp members so as to embrace the bar portions 17—17, and so as to extend outwardly from between the opposite upper end bar portions 18—18. It will be seen that this arrangement is such that the looped portions 12 of the strip 10 tends to clamp the clasp members together, especially when a pull is exerted on the clasp members which tends to straighten the loop 12. It will also be observed that the upper end bar portions 18—18 serve to tighten the loop 12 around the bars 17—17.

The flexibility of the looped portion of the strip 10 permits spreading of the clasp members 13 and 14, such spreading being yieldingly resisted by the loop 12, the bottom portion 19 thereof being caused to stretch when

the clasp members are spread. When the clasps are spread, they are swung about their upper ends, which serve as fulcrums by engaging the adjacent portion of the loop which is then supported by the bar portion 18 of the opposite clasp member. Thus, the bottom side of the intermediate bars 17-17 are caused to swing about a radius of material length so that a material amount of stretching is required of the bottom portion 19 of the loop.

The opening 16 in the clasp member 13 may conveniently but not necessarily be circular as shown, and the opening 16 in the clasp member 14 is preferably elongated, the upper portion of the openings 16 of the two clasp members being in registry with one another, and the lower portion of the opening in the clasp member 14 extending below the lower portion of the opening in the clasp member 13. At the bottom of the opening in the member 14, I prefer to provide teeth-like formations 20 which are adapted to bite into the tab of the napkin to effectively prevent slipping thereof from between the clasp members.

The belt proper 5 is preferably made of elastic material as are also the flexible fabric parts of the pendants 8 and 9, and these parts are also preferably made of comparatively narrow elastic ribbon, for instance, an elastic ribbon about $\frac{3}{8}$ inches in width. The clasp members 13 and 14 are preferably made of a non-metallic material such as celluloid, which material may also conveniently be used in manufacturing the adjusting buckles 6, 7 and 11. The weight and dimensions of the parts of my sanitary belt are thus maintained at a minimum so as to secure the maximum of comfort to the wearer.

I am aware that changes may be made in the sanitary belt structure above described without departing from the spirit of my invention, the scope of which should be determined by reference to the following claims, the same being construed as broadly as possible consistent with the state of the art.

I claim as my invention:

1. In a device of the class described, a loop member formed of two folds of relatively flexible material, a pair of clasps formed of relatively flat material, each clasp having an opening adjacent the upper end thereof and a second opening spaced from said first opening to provide a relatively flat bar, the folds of said loop extending between said clasps at the upper portion thereof, thence passing outwardly through said first openings, around said bars and through said second openings so as to join each other.

2. In a device of the class described, a loop member formed of two folds of relatively flexible material, a pair of clasps formed of relatively flat material, each clasp having an opening adjacent the upper end thereof

and a second opening spaced from said first opening to provide a relatively flat bar, one of said clasps having a portion of the wall of said second opening opposite said first opening provided with irregularities which will tend to prevent slippage of textile material extending through said opening, the folds of said loop extending between said clasps at the upper portion thereof, thence passing outwardly through said first openings, around said bars and through said second openings so as to join each other.

3. In a device of the class described, a loop member formed of two folds of relatively flexible material a pair of clasps formed of relatively flat material, each clasp having an opening adjacent the upper end thereof and a second opening spaced from said first opening to provide a relatively flat bar, the folds of said loop extending between said clasps at the upper portion thereof, thence passing outwardly through said first openings, around said bars and through said second openings so as to join each other, and means provided on said loop member for tightening the engagement thereof with said clasps.

4. In a device of the class described, a loop member formed of two folds of relatively flexible material, a pair of clasps formed of relatively flat material, each clasp having an opening adjacent the upper end thereof and a second opening spaced from said first opening to provide a relatively flat bar, one of said clasps having a portion of the wall of said second opening opposite said first opening provided with irregularities which tend to prevent slippage of textile material extending through said opening, the folds of said loop extending between said clasps at the upper portion thereof, thence passing outwardly through said first openings, around said bars and through said second openings so as to join each other, and means provided on said loop member for tightening the engagement thereof with said clasps.

5. In a device of the class described, a loop member formed of two folds of relatively flexible material, a pair of clasps, each clasp having an opening adjacent the upper end thereof and a second opening spaced from said first opening to provide a transverse bar, the folds of said loop extending between said clasps at the upper portion thereof, thence passing outwardly through said first openings around said bars and through said second openings so as to join each other, and means provided on said loop member for tightening the engagement thereof with said clasps.

6. In a device of the class described, a loop member formed of two folds of relatively flexible material, a pair of clasps, each clasp having an opening adjacent the upper end thereof and a second opening spaced from said first opening to provide a transverse bar,

one of said clasps having a portion of the wall
of said second opening opposite said first
opening provided with irregularities which
will tend to prevent slippage of textile ma-
terial extending through said opening, the
5 folds of said loop extending between said
clasps at the upper portion thereof, thence
passing outwardly through said first open-
ings, around said bars and through said sec-
ond openings so as to join each other, and
10 means provided on said loop member for
tightening the engagement thereof with said
clasps.

ARTHUR W. GAVITT.
